United States Patent Office

Des. 226,707
Patented Apr. 17, 1973

226,707

TRACTOR

Robert A. Skyer and Mitchell E. Kolak, Palatine, and
Harry R. Wilson and Joseph H. Konefes, Libertyville,
Ill., assignors to International Harvester Company, Chi-
cago, Ill.

Filed Apr. 16, 1971, Ser. No. 134,912

Term of patent 14 years

Int. Cl. D12—09

U.S. Cl. D14—3 A

FIG. 1.

FIG. 2.

FIG. 4.

FIG. 1 is a three-quarter perspective view as seen from the right front of the tractor embodying our new design;

FIG. 2 is a three-quarter perspective view as seen from the right rear thereof;

FIG. 3 is a side elevational view thereof; and

FIG. 4 is a top plan view thereof.

The portions shown in broken lines on the drawings are included for illustrative purposes only.

We claim:

The ornamental design of a tractor, substantially as shown and described.
